UNITED STATES PATENT OFFICE.

DENNIS W. MULLEN, OF BROCKTON, MASSACHUSETTS.

SELF-FEEDING BOTTLE FOR LIQUID POLISHES AND THE LIKE.

Application filed October 18, 1926. Serial No. 142,165.

This invention relates to a self-feeding bottle designed especially for dispensing liquid polishes.

In the manufacturing of patent leather shoes it not infrequently happens that a shoe becomes marred or scratched and when this happens the damage is usually repaired by rubbing a specially prepared polish on the marred portion. Some polishes which are used for this purpose are in liquid form. It is customary to keep the liquid in bottles and when the workman desires to repair a marred portion he removes the stopper from the bottle, places his finger or a swab against the top of the bottle so as to close the opening in the neck of the bottle and then tips the bottle up to allow the liquid to flow onto his finger or the swab. The liquid which is thus deposited on the finger or swab is then transferred to the shoe and rubbed over the damaged portion. This method of dispensing the polish is more or less wasteful because usually a good deal more polish is deposited on the finger or swab than is necessary to repair the damage, and the liquid is apt to be spilled as the bottle is turned over.

One of the objects of my present invention is to provide an improved bottle by means of which the liquid or polish may be dispensed without waste and without the necessity of picking the bottle up and turning it over, as has been heretofore the general custom. This is accomplished herein by providing the bottle with a stopper having an opening therein and employing a frame which is secured in the opening and depends into the bottle to the bottom thereof, said frame supporting two freely-rotatable guide rollers, one at the top and one at the bottom over which passes a feeding belt. The upper bight of the belt is situated flush with the top of the stopper so that the operator can draw his finger one or more times across the belt, this operation moving the belt around the rollers, and bringing to the top a portion of the belt which has been immersed in the liquid in the bottle, and also transferring to the finger some of the liquid carried by the belt.

In order to give an understanding of the invention I have illustrated in the drawings a selected embodiment thereof which will now be described after which the novel fea-

tures will be pointed out in the appended claims.

Fig. 1 is a vertical sectional view through a bottle embodying my invention;

Fig. 2 is a top plan view of the stopper;

Fig. 3 is a section on the line 3—3, Fig. 1, 60 1 indicates a container preferably having the general form of a bottle provided with a neck 2. This container as shown is supported in a standard or support 3 so that it will rest firmly on a table or bench. The 65 neck of the bottle 2 receives a stopper 4, which may conveniently be made of metal. This stopper has an opening 5 extending therethrough and it is shown as surrounded by a jacket 6 of rubber or some yielding 70 material which produces a tight joint between the stopper and the bottle neck.

The stopper 4 has a frame 7 secured thereto and depending therefrom. This frame comprises the two side members 8 75 which are connected by cross members 9. The frame is supported at its upper end upon a pin 10 which extends transversely through a stopper and the upper ends of the side members 8 are shown as set in recesses 80 11 formed in the walls of the opening 5. This frame carries at its upper end a guide roller 12 and at its lower end another guide roller 13. The roller 12 is shown as journalled on the pin 10 and the roller 13 is 85 shown as rotating freely on a pin 14 which is carried by the lower end of the frame.

15 indicates a feed belt which extends around the guide rollers 12 and 13. The upper guide roller is situated so that it is 90 substantially flush with the top of the closure or stopper 4 and the frame has such a vertical dimension that the lower roller is located adjacent the bottom of the bottle 1.

16 indicates a cap which is screw threaded to the upper end of the stopper 4 and when the cap 16 is removed the upper roller 12 is exposed.

The bottle is shown as containing a polishing liquid 17. The lower end of the 100 frame and the lower portion of the belt are immersed in the liquid. As the belt is turned the portion thereof which has been immersed in the liquid will be carried up over the upper roller 12 thus bringing to the 105 mouth of the stopper 4 a portion of the belt which is coated with the liquid polish.

In using the device the operator will

simply remove the cap 16 and then wipe his finger or swab across the upper turn of the belt. This operation serves to turn the belt around the rolls and thus bring the wet portion of the belt into position at the opening of the stopper.

The belt will preferably be of material which is sufficiently absorbent so that the portion which is exposed at the top of the 10 stopper will carry more or less of the polish.

For repairing ordinary scratches or mars it will be sufficient if the operator passes his finger once or twice across the belt as this 15 operation will transfer to the finger a sufficient amount of polish to repair the damage. Each pass of the finger turns the belt and brings a fresh portion thereof at the upper turn so that the portion of the belt which is 20 exposed through the top of the opening 5 is always loaded with the polish.

The advantage of employing the frame 7 is that the lower end of the belt is always maintained closely adjacent the bottom of 25 the bottle, and, therefore, even though there

is only a small amount of liquid in the bottle the lower end of the belt will be immersed therein.

I claim:

A self-feeding bottle for liquid polishes comprising a bottle having a neck, a stopper fitting the neck and having an opening therethrough, two opposed walls of said opening being each formed with a vertical groove, a frame rigid with the stopper, said frame comprising two parallel connected side members, the upper ends of the side members fitting the grooves in the stopper and the frame depending from the stopper into the bottle, guide rolls carried by the 40 frame at the upper and lower ends thereof, the upper guide roll being located substantially flush with the top of the closure, and an endless feeding belt extending beyond the guide rollers, said stopper and 45 frame which is rigidly connected thereto being removable from the bottle as a unit.

In testimony whereof, I have signed by name to this specification.

DENNIS W. MULLEN.
